UNITED STATES PATENT OFFICE.

EDGAR B. TOLMAN, JR., OF CHICAGO, ILLINOIS.

ASH-CONVEYER SYSTEM.

Application filed September 5, 1922. Serial No. 586,162.

To all whom it may concern:

Be it known that I, EDGAR B. TOLMAN, Jr., a citizen of the United States, residing at Chicago, in the county of Cook and State of Illinois, have invented certain new and useful Improvements in Ash-Conveyer Systems, of which the following is a description.

My invention relates to improvements in ash conveyer systems, and more particularly to means for simplifying the structure of such systems and increasing their efficiency, and in which the wearing parts may be easily removed for renewal or the like whenever necessary.

Another object of my invention is to provide ash intakes in said line into which the ash may be charged from the furnace and through which connection a steam jet or the like may be passed for the purpose of boosting the velocity of the ash thereat.

Another object of my invention is to provide an intake booster as above described, in which the wear-back portion thereof may be easily removed from the line without disassembling or removing any other part of the fitting.

Another object of my invention is to provide an intake booster of such a shape and form that the ash admitted thereto at one end will be directed into the path of the jet of steam, air, or the like, and be discharged at the opposite end through an opening whose axis is in alignment with the axis 35 of the jet, and in which fitting there is provided another or main ash intake having a removable cover and into which the ashes may be admitted from the boiler directly into the path of the jet in alignment with the jet and the outlet.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view showing a typical installation;

Fig. 2 is an elevation thereof;

55

Fig. 3 is a plan view of the booster intake fitting;

Fig. 4 is a section taken substantially on line 4—4 of Fig. 3;

60

Fig. 5 is an end view of the fitting;

65

Fig. 6 is a section taken substantially on the line 6—6 of Fig. 3, and

Fig. 7 is a section taken substantially on the line 7—7 of Fig. 3, and;

70

Fig. 8 is a section taken through an end fitting.

In the drawings, wherein I have illus-

trated the preferred embodiment of my in-

vention, 1 represents the boilers, which may

be of any construction or type whatsoever

75

and from which the ashes are to be with-
drawn and conveyed away. 2 represents a

portion of the ash conveyer lying substan-

75

tially in a horizontal plane below the level

of the ash doors of the boilers, this con-

75

veyer line inclined upwardly at one end

80

beyond the line of the boilers as at 3, and

85

terminating in an impact box or target 4,

85

at its upper end and from which the ashes

85

may be discharged into any convenient re-

90

ceptacle or onto the ground, as desired. In

90

the conveyer line, adjacent each of the boil-

95

ers is an ash intake 5, into which the ashes

95

from the boiler may be discharged and

100

carried through the conveyer line to the

100

target 4, each of the intake fittings pref-

105

erably having a removable cover 6 suitably

105

arranged thereon.

At the bend in the line is a booster member

90

7, having a steam jet inlet 8 leading thereto

95

the same controlled by any suitable valve 9,

95

to boost the velocity of the ashes at this

100

point and to move them directly to the target

100

box 4, at increased velocity. By placing a 45°

105

booster fitting at this point, as shown, there

105

is a saving over the number of fittings re-

105

quired and also in amount of steam necessary

105

for the conveying, over the usual type of

105

conveying line wherein the portion 3 of

105

the line is extended vertically and thence

105

horizontally to discharge into the target

105

box.

An intake booster fitting 9 may be ar-

105

ranged at any one of the ash intakes inter-

105

mediate the ends of the line, as shown, and

105

by means of which the velocity of the ashes

105

passing therethrough may be increased to

105

above that just preceding the point of entry

of ashes thereto, and in which the ashes discharged directly from the boiler will be conveyed by the boosting jet. This booster intake fitting comprises two parts 10 and 11, of any desired metal—that of the part 11 being either of the same hardness as that of the part 10, or of a greater hardness, as desired, and removably secured together by means of detachable bolts 12 so as to form a casing. Both of the ends of the fitting are flanged, as at 13, and 14, and each of the flanges are provided with elongated bolt holes 15 therethrough for detachably connecting the fitting to the adjacent line fittings.

At one end of the fitting, the part 10 is provided with a pair of inlets 16 and 17, the former being the inlet nozzle for the jet of steam, air or the like, and the latter being for the admission of ash or other material being conveyed through the section, these inlets being laterally spaced apart and opening into a common chamber. The inner face 18 of the wear part 11 is preferably flat or straight, as most clearly shown in Figs. 6 and 7. The jet inlet nozzle 16 is preferably screwed into a threaded plug, (see Fig. 4) set in when the parts are cast, because as the part 10 is of a very hard material it would be rather difficult to thread the same and secure the nozzle thereto after casting. The plug may be of softer metal easily threaded.

At the opposite end of the fitting and in axial alignment with the steam jet inlet is an outlet port 19 formed jointly by the members 10 and 11, as shown. The inner surface of the wear-back member 11 is inclined from the intake to the outlet so that the material admitted through the inlet port will be deflected directly into the jet coming through the jet inlet, the same carrying the charge outwardly through the discharge outlet 19. The jet tends to create a vacuum or suction which will draw the ash impelled through the inlet 17, and gets back of said ash and pushes, forces or shoots the ash outwardly through said outlet.

The wear-back member at the point of greatest wear is straight, as before mentioned, and is preferably thickened in cross section so that the longevity of the parts is greatly increased. The meeting edges or sides of the wearback member or body part respectively are preferably flanged and in each of these meeting edges is formed a series of cooperating stepped portions, shoulders or tongue and grooves into which a packing material may be inserted when the two parts are assembled. Whenever it is desired to renew the wear-back member after the booster is assembled in the conveyer line, the bolts 12 are loosened and said wear-back member may be removed without disturbing the rest of the line.

Intermediate the ends of the fitting in the part 10 there is formed a main ash intake 20, and through which the ashes from the boilers are drawn directly into the conveying line. A removable cover 21 is generally held in place over the opening 20, this cover fitting air tight but adapted to be very easily removed when desired. The opening 20 permits the discharge of the ashes directly into the path of the steam jet and the same blows said ashes through the outlet 19 and through the line.

By the use of my improved booster intake fitting the number of fittings in the line may be materially reduced, inasmuch as in this case the ash intake and booster fitting are combined in one, thus greatly reducing the cost of the installation.

In Fig. 8 I have shown a type of fitting that may be used at the end of the line, the same being open to permit the admission of air, and in this particular one it is shown with an ash or material inlet. Referring to Fig. 8, a nozzle 28 is carried by the support 26 which may be arranged on a spider 27, the same supporting and centering the nozzle. Obviously, the nozzle may be connected with a steam line or the like in any suitable manner. The inlet end, as shown, is slightly flared. Where desired, however, a standard fitting similar to the fittings 5 may be employed and a flared end 30 (see Figs. 1 and 2) may be secured thereon, this carrying the nozzle exactly similar or in an equivalent manner to the carrying of the nozzle 28, as shown in Fig. 8. On short lines this extra nozzle is not always required, but there are some installations where it is preferred and as before mentioned, it may be modified if so desired. It should also be understood that while I have illustrated a fitting that is a booster and ash intake with the main line of the conveyer extending straight, the fitting may be any type. For example, a fitting similar to 7 or an elbow turned in a horizontal plane might be provided with the ash intake opening. This is merely mentioning one adaptation of the construction, others being obvious to those skilled in the art.

Having thus described my invention it is obvious that various immaterial modifications may be made in the same without departing from the spirit of my invention; hence I do not wish to be understood as limiting myself to the exact form, arrangement, construction and combination of parts herein shown and described or uses mentioned.

What I claim as new and desire to secure by Letters Patent is:

1. A conveyer fitting having a jet inlet, an ash inlet, an outlet whose axis is in alignment with the axis of said jet inlet, a second ash intake, and a detachable wear-back mem-

ber for directing the ash from said first-mentioned inlet into said jet.

2. A booster intake fitting having a jet inlet, an ash inlet, an outlet whose axis is in alignment with the axis of said jet inlet, a second ash intake, and an inclined detachable wear-back member for directing the ash into said jet.

3. A booster intake fitting having a jet inlet, an ash inlet, and an outlet whose axis is in alignment with the axis of said jet inlet, an ash intake intermediate said ash outlet and ash inlet, and an inclined detachable wear-back member for directing the ash into said jet.

4. A booster intake fitting having a jet inlet, an ash inlet, and an outlet whose axis is in alignment with the axis of said jet inlet, an ash intake intermediate said ash inlet and outlet and whose axis is perpendicular to said beforementioned axes, and an inclined detachable wear-back member for directing the ash into said jet.

5. In a booster fitting of the kind described and in combination, a plurality of cooperating parts detachably secured together to provide a casing having an ash inlet and outlet at opposite ends and constructed for attachment in a conveying line, said casing inlet and outlet offset from each other, said casing provided with an inlet for an impelling fluid arranged substantially opposite said outlet in alignment therewith, and an ash intake intermediate said ends.

6. In a booster fitting of the kind described and in combination, a plurality of cooperating parts detachably secured together to provide a casing having an ash inlet and outlet at opposite ends and constructed for attachment in a conveying line, said casing inlet and outlet offset from each other, said casing provided with an inlet for an impelling fluid arranged substantially opposite said outlet in alignment therewith, and an ash intake intermediate said ends and

whose axis is perpendicular to the axis of said outlet.

7. A booster fitting having an ash intake and a jet intake at one end, a single outlet at the other end in alignment with said jet intake, a second ash intake through the side of said fitting intermediate its ends, and a detachable wear-back member for directing the ash into said jet.

8. A booster fitting having an ash intake and a jet intake at one end spaced laterally of one another, a single outlet at the other end of the fitting in alignment with the axis of the jet, and a second ash intake through the side wall of said fitting intermediate said ends, said fitting including a removably detachable wear-back member extending from said outlet to said first mentioned ash intake and forming a part of said outlet.

9. In a system of the kind described and in combination, an ash conveyer line lying substantially in a horizontal plane and having ash intake fittings having openings and arranged at suitable points therealong and thence inclined upwardly to its outlet at an oblique angle, and a booster fitting in said line at the bend thereof, the intake end of said booster fitting connected to the horizontal portion of the line and the discharge end thereof connected to said upwardly-extended portion, one of said ash intake fittings having its line intake offset laterally from its discharge, a fluid booster jet directed through said discharge to said last mentioned fitting, and an end fitting provided with an air inlet and with a booster jet adjacent thereto.

In testimony whereof, I have hereunto signed my name in the presence of two subscribing witnesses.
